UNITED STATES PATENT OFFICE.

GARRETT J. STANTON, OF LOS ANGELES, CALIFORNIA.

WALL CONSTRUCTION.

1,357,125.

Specification of Letters Patent. Patented Oct. 26, 1920.

Application filed January 14, 1919. Serial No. 271,006.

To all whom it may concern:

Be it known that I, GARRETT J. STANTON, a citizen of the United States, and resident of Los Angeles, in the county of Los Angeles, State of California, have invented certain new and useful Improvements in Wall Construction, of which the following is a specification.

My invention relates primarily to wall construction of the hollow type and has for its object the construction of a hollow wall having a continuous channel extending horizontally along each course, each channel being connected at its ends to the next adjacent upper and lower channels respectively whereby a continuous air channel is formed the entire height of the wall, the channel extending in opposite directions in each alternate course whereby a draft is created and caused to flow through the wall thereby materially reducing the temperature of the interior of the building.

I accomplish this object by the wall construction described herein and illustrated in the accompanying drawings forming a part hereof in which:

Figure 1 is a perspective view of a fragment of a wall constructed according to my invention.

Fig. 2 is a perspective detail, partly broken away, of one form of my tile.

Fig. 3 is a perspective view of my corner tile.

Fig. 4 is a cross-sectional perspective showing the method of connecting the air channels.

In the drawings my wall proper is formed of courses in the usual manner, each course being composed of pairs of tile 6 which are substantially U-shaped in cross section. The tile of each pair are laid reversely to each other; that is the open faces of each pair of tile are positioned facing each other

thereby forming a rectangular channel 7. At the ends these channels are connected by a passage 8 which extends through the body of the tile as best shown in Fig. 4. It will be understood that these connections are provided at alternate ends of the wall courses. In other words the connection from the lower channel to the one next above will be at one end of the wall and the connection from this last channel will be at the opposite end of the wall thus causing the air to pass entirely along each course before entering the course next above, thereby forming a continuous air space the entire length and height of the wall. In Fig. 3 I have shown my form of corner tile. In this tile the channel 9 is turned at a right angle near its end to connect with the channel of the wall forming the side.

Having described my invention what I claim is:

A wall construction composed of a plurality of pairs of tile, said tile being substantially U-shaped in transverse cross section, the tile of each pair being laid with their open sides in register and forming a continuous air channel the entire length of each course, the tile of each course being laid reversely to the adjacent tile in each adjacent course, the tile forming the ends of said wall having a portion of the horizontal connecting members cut away to form a connection between two adjacent air channels, said connections being positioned at opposite ends of the wall in adjacent courses, whereby a continuous air channel is formed extending in alternate directions through adjacent courses throughout the entire height of the wall.

In witness that I claim the foregoing I have hereunto subscribed my name this 21st day of December, 1918.

GARRETT J. STANTON.
